UNITED STATES PATENT OFFICE.

WILLARD I. LEWIS, OF WALPOLE, MASSACHUSETTS.

AUTOMATIC WEB-GUIDING DEVICE.

No. 905,720.

Specification of Letters Patent.

Patented Dec. 1, 1908.

Application filed September 25, 1907. Serial No. 364,460.

To all whom it may concern:

Be it known that I, WILLARD I. LEWIS, a citizen of the United States, residing at Walpole, in the county of Norfolk, State of Massachusetts, have invented a certain new and useful Improvement in Automatic Web-Guiding Devices, of which the following is a specification, reference being had therein to the accompanying drawings.

- 10 The present invention is in the nature of an improvement upon the automatic web guiding device which is described in United States Letters Patent No. 678,121, granted to me under date of July 9, 1901. The device of the said patent acts to cause the selvages or margins of an advancing continuous web—of cloth, for instance—to follow along predetermined lines as the web is operated upon, or wound.
- 20 It comprises, essentially, a detector-roll contrived to ascertain the positions of the respective selvages or margins of the web, traveling selvage-bars or blocks, and automatic devices under control of the said detector-roll whereby the said selvage-bars or blocks are adjusted transversely with relation to the width of the web to correspond with the positions assumed by the respective selvages or margins on their way to the 30 guiding device, and are operated to conduct the respective selvages or margins into the predetermined paths.

In the machine described and shown in the patent aforesaid, the radially-movable pins of the detector-roll are spring-actuated, each pin having applied thereto a spring by which it normally is held in a position in which its outer end projects from the periphery of the roll, in readiness to be pressed 40 upon by a marginal portion of the web. In the said machine, also, as the detector-roll rotates the inner ends of those pins which are covered by the marginal portions of the web, and pressed radially inward thereby, 45 engage directly with the cam-faces of the ends of the sleeves that are employed in connection with the annuli, serving as cam-tracks for the selvage-bars or blocks, and thereby either act as stops to limit the extent of the movement of the said sleeves 50 and annuli toward the middle of the machine, or serve, as they are caused to travel in contact with the said cam-faces, to force the cam-sleeves and annuli outward from the middle, according as the selvages or 55 margins of the web sway inward or outward.

The present invention consists in various features of improvement dispensing with the employment of springs in connection with the detector-pins of the detector-roll. 60 Also, securing a quieter and easier action in effecting the automatic adjustment of the edge-positioning bars or blocks, or of the other edge-positioning devices which may be employed for the purpose of shifting the 65 selvages or margins of the web into the required paths. Also, largely reducing the opportunity and occasion for wear. Also, involving a more convenient and advantageous construction of the principal working parts, and providing adjustments which enable certain important results to be attained in the use of the machine.

A machine embodying in preferred form the different features of the invention is 75 illustrated in the drawings, in which latter,

Figure 1, Sheet 1, is an end elevation of the said machine. Fig. 2, Sheet 2, is a gear elevation thereof. Fig. 3, Sheet 3, is a view showing one end-portion of the detector-roll, 80 and certain parts in connection therewith, mainly in central longitudinal section. Fig. 4, Sheet 3, shows in side elevation, detached, one of the heads or spiders of the detector-roll, and Fig. 5, same sheet, shows the same 85 in end elevation viewed from the left hand side in Fig. 4. Fig. 6, Sheet 3, is a plan of one of the pin-carrying bars of the detector-roll, and Fig. 7, same sheet, is an end elevation of the bar shown in Fig. 6. Fig. 8, 90 Sheet 1, is a side or end elevation of one of the yokes which are employed in connection with the detector-mechanism for effecting the automatic adjustment of the annuli, and Fig. 9, same sheet, is a plan of the yoke 95 shown in Fig. 8. Fig. 10, Sheet 1, shows an annulus in side elevation, and Fig. 11, same sheet, is a plan thereof. Fig. 12, Sheet 1, is a plan of the slotted piece with which the pivot at the delivery side of an annulus is 100 engaged.

The invention is illustrated in the drawings as embodied in a machine comprising, essentially, a detector-roll carrying detector devices, edge-positioning devices, automatic 105 means of adjusting the said edge-positioning devices under the control of the detector-devices, means for adjusting the detector-devices at will to suit the width of web being operated upon, or the state in which such 110 web passes to the machine, without interfering with the automatic operation of the

machine, means for rotating the detector-roll and edge-positioning devices by power to conduct the web through the machine, and means for adjusting the edge-positioning devices to vary transversely the path of the edge of the web in being delivered by the devices last named. In addition, the machine is equipped with directing and tension rods or rolls for guiding the web into the machine, to the detector-roll and edge-positioning devices, and from the machine, and producing in the web the proper tension to secure the required action of the detector and edge-positioning devices.

Having reference to the drawings,—at *a*, Fig. 1, is indicated a web passing through the machine, the course of the said web, and the direction of its movement, being indicated by arrows in connection therewith in the said figure.

The machine-frame is designated 1.

At 2, Fig. 1, is a guide-rod or roll mounted in the said frame at the side where the web enters, and the web in passing into the machine being led under and part-way around the said guide-rod or roll.

At 3 is a rotatable guide and tension roll having its journals mounted in bearings in the top of the machine-frame. The web passes from guide-rod or roll 2 upward to and partly around roll 3, and from the latter passes downward to and partly around the detector-roll 4. From the roll 4 the web passes upward to and around the upper portion of the rotatable series of edge-positioning bars 5, 5, etc., and then to, under, and partly around the guide-rod or roll 6 on its way out of the machine.

Referring briefly to the features, in general, of the machine,—in Fig. 3, which shows certain details of the construction at the end of the machine which is represented in Fig. 1, 7, 7, etc., are the radially movable detector members or pins of that end of the detector-roll 4 which is shown in such figure, and 8 is the cam-sleeve, or as it also may be termed, shifter-cam, that is employed at such end, the said cam-sleeve, or shifter-cam, being mounted, as in the case of that of the patent of July 9, 1901, upon the shaft, 9, of the detector-roll with capacity to move lengthwise with respect to the shaft, but being held from rotation with the shaft. At 10 is a yoke, shown in place in the machine in Fig. 1, and separately in detail in Figs. 8 and 9, a portion thereof being shown in section in Fig. 3, the said yoke constituting a connector between the cam-sleeve or shifter-cam and the corresponding annulus shown at 11, and being connected pivotally with such annulus at the leading side of the center of the latter, and the annulus being arranged to swing transversely on a vertical pivot 12 (Figs. 2, 10 and 11) located at the opposite *i. e.* delivery side of the said center.

The yoke, 10, as shown separately in detail in Figs. 8 and 9 is formed with a hub, 10^a, which fits upon the exterior of the outer end of the cam-sleeve and is made fast thereto. The yoke is formed, also, with upper and lower arms or branches 10^b, 10^b. The annulus 11, is formed at its outer side with the track-surface, 11^a, and with arms 11^b, 11^b, at its leading side, and an arm 11^c at its delivery side. The connection between the yoke and the leading side of the annulus is established by means of pivots which serve to join the arms 10^b, 10^b, with the arms 11^b, 11^b. Arm 11^c of the annulus carries or is provided with the pivot-pin 12. As in the patent aforesaid, the parts just mentioned are duplicated at the respective sides of the machine, although in some instances I may employ only one set of the said parts. At 13, 13, etc., Figs. 1 and 2, are the antifriction rolls which are carried by the edge-positioning bars 5, 5, etc., and engage with the track-surface 11^a (Figs. 10 and 11) of the annulus. As in the said patent, the bars 5, 5, etc., are arranged in a cylindrical series upon a rotating support, and connected together in pairs (each of such pairs comprising a bar at the one end of the rotating series and the corresponding bar at the other end of such series) by contracting spiral springs (shown at 72, 72, etc., in the patent) which tend to draw the said bars lengthwise toward the middle of the width of the machine so as to hold the rolls 13, 13, etc., in contact with the track-surfaces of the respective annuli. As in the machine of the patent, the pressure which is transmitted through the said rolls to the annuli tends to swing each of the latter inward at its leading side, and operates to move therewith the connected cam-sleeve until such movement is limited by the detector-pins. Thereby, in the same general manner as in the machine of the patent in question, the leading side of each annulus is pressed inward at all times to the extent permitted by the detector-pins at the corresponding side of the machine, that is to say, to an extent which at any given instant conforms to the line on which the selvage or margin at such side is traveling in arriving at and passing upon the edge-positioning bars. Briefly described, the rotating support for the edge-positioning bars 5, 5, etc., comprises, essentially, the rotatable shaft 14, Figs. 1 and 2, which is mounted in suitable bearings at 15, 15, in connection with the opposite side frames of the machine, the heads 16, 16, which are fixed upon the said shaft, and the guide-rods 17, 17, etc., having their opposite ends fixed in the respective heads, the said bars 5, 5, etc., being mounted upon the said guide-rods with capacity to slide upon the latter in the direction of the length thereof. The outer surfaces of the bars 5, 5, etc., are suitably prepared to take hold of the marginal 130

portions of the web, as by roughening or clothing the same with frictionally adhesive material at 18, 18, etc., to render the said bars efficient in carrying such portions of the 5 web outward with them when the bars are moved toward the ends of the machine.

The preferred embodiment of the features of the present invention involving the detector-pins, the means for adjusting the detector devices transversely of the machine to adapt the machine to operate upon webs of different widths, and the movable members interposed between such pins and the cam-sleeve are illustrated in Fig. 3.

15 Fig. 3 shows a portion of the length of one end-section of the detector-roll, the shell of the said end-section being fixed at its outer end upon the exterior surfaces of bars 19, 19, etc., the said bars also extending in the direction of the length of the roll, and in turn being secured upon the longitudinally-extending portions of arms 20, 20, etc., of the head 20^a which is sleeved upon the shaft 9.

For the reception of the detector-pins, 25 each bar 19 has formed therein a series of radial holes 19^a, 19^b, etc., Figs. 6 and 7, constituting pockets in which the detector-pins 7, 7, etc., are contained, and within which the said pins are movable radially. The portion of the said shell which covers the said bars has formed therein holes registering with those in the respective bars, and through which the outer ends of the pins may project.

In order to limit the extent of the outward movement of the pins, the holes in the shell are made less in diameter than those in the bars 19, 19, etc., and the outer portions of the pins are made smaller in diameter than the inner portions thereof, a shoulder being 40 formed at the exterior of each pin at an intermediate point in the length of the latter. Thereby, when outward movement of the pins within their pockets occurs, the shoulders of the pins engage with the margins of 45 the holes in the shell and prevent the pins from leaving the pockets.

As previously indicated herein, the springs of the patent of July 9, 1901, employed in connection with the detector-pins for projecting them radially outward, are dispensed with under the present invention, and gravity alone is depended upon for causing the detector-pins to work radially in and out within the pockets. Thus, the detector-pins are capable of free movement within their pockets, so that as a given series of the pins is carried upward to the top side of the detector-roll by rotation of the latter, the pins will gravitate inward, as at the top in Fig. 3, and that 55 in being carried around to the bottom side of the roll, they will tend to gravitate outward again, into the radial position of the outermost two pins in such figure which are not restrained by the web *a*.

60 Briefly summarizing the incidents in the

detecting action of the pins, it may be stated that in the use of the machine the web *a*, in passing under and partly around the detector-roll, makes close contact with the periphery of the latter as indicated in Fig. 3. 70 As the turning movement of the detector-roll proceeds, in unison with the travel of the web, and carries a given series of the detector-pins around from the upper side of the roll downward to the lower side thereof, the 75 pins of the said series tend to slide radially outward. Those thereof which occupy pockets that are covered or closed by the marginal portion of the web are supported by the web in approaching the lowermost position, and 80 thereby held inward, as represented in Fig. 3. Those pins which are beyond the selvage or margin of the web are permitted to slide downward and outward under the influence of gravity until their movement radially outward is arrested by engagement of their shoulders with the edges of the shell around the holes therein, as shown in Fig. 3 in the case of the two outermost detector-pins.

For convenience in operating upon webs 90 of different widths, the detector-roll is made of the well-known telescoping construction which is more or less common in the case of the rolls and cylinders employed in web-handling machines. Only the end-section at 95 one side of the machine is represented in Fig. 3, inasmuch as the general character of the telescoping construction is well-known to those skilled in the art. By lengthening or shortening the roll the length thereof is made 100 to correspond approximately with the width of a given web to be operated upon, in the state of lateral extension in which it arrives at such roll, and thereby the series of detector-pins at the respective ends of the roll are 105 adjusted into proper working positions with relation to the selvages or margins of the web. Usually, the adjustment will be such that each selvage or margin will travel at about mid-length of the series of detector-pins. For the purpose of enabling the adjustment of the length of the detector-roll to be effected conveniently, the head 20^a is 110 mounted upon shaft 9 with capacity to slide thereon in the direction of the length of such shaft, and a screw-threaded adjusting shaft 21 is provided. The shaft 9 is hollow or tubular, and the screw-threaded adjusting shaft extends lengthwise through the same. Bearings for the latter shaft are fitted within 115 the opposite ends of the hollow shaft 9, one of such bearings being shown at 22, Fig. 3. A crank-handle, 23, is fixed upon either or each end of the adjusting shaft to enable the latter to be turned by hand. In connection 120 with each end-section of the detector-roll, a nut, 24, is employed within the hollow shaft 9, the said nut being engaged with the threaded portion of the corresponding end of the adjusting shaft, so that when the said 125

shaft is turned the nut will be moved in the direction of the length of the hollow shaft. In order to transmit this movement to the corresponding section of the detector-roll, 5 connection is established between the said nut 24 and the spider or head 20, 20^a, by means of a key, 25, which last is secured in place within the hub of the said spider or head by means of screws 26, 26, and provided 10 at its opposite ends with projections extending radially inward and receiving the nut between them. This key occupies a longitudinal slot, 27, formed in the shell of the hollow shaft 9, within which slot the key slides as 15 the nut, spider or head, etc., are changed in position. The key serves also as a means of causing the end-section of roll 4 to rotate in unison with the hollow shaft 9 when the latter is turned. The other end-section (not 20 shown) of the detector-roll is similarly constructed and connected with the hollow shaft 9, and with the adjusting shaft 21, with the difference that the direction of the screw-thread on the corresponding portion of the 25 latter shaft is reversed, as usual in the like constructions, so that when the adjusting shaft is rotated the respective end-sections shall be adjusted simultaneously in opposite directions in order to increase or decrease the 30 effective length of the detector-roll, according as the said sections are moved toward or away from each other.

It previously has been mentioned herein that in the case of the machine described in 35 the patent of July 9, 1901, the inner ends of those pins which are covered and pressed radially inward by the marginal portions of the web engage directly with the cam-faces of the cam-sleeves that are employed in connection with the annuluses. In the present 40 invention, I interpose a movable member between detector-pins and cam-face, and thereby avoid the results of direct engagement. The invention, in its broader phases, 45 is not limited with respect to the precise form and construction of this movable interposed member, nor with respect to the precise relations between such member and the parts with which it co-operates. In the 50 illustrated embodiment of the invention a longitudinal movable bar 28 is provided in conjunction with each series of the detector-pins 7, 7, etc. This bar constitutes, in the said embodiment, the movable interposed 55 member aforesaid. On the one hand, it engages with the particular pin (of the series of detector-pins with which it co-operates) which indicates the position of the selvage or margin of the web, and on the other hand 60 it co-acts with the cam-face of the cam-sleeve in substantially the same manner as a pin co-acts with the cam-face of the sleeve in the prior patent for the purpose of determining the position of the corresponding 65 annulus. Each movable bar 28 is held in

place close to the inner side of the corresponding fixed bar 19 by means of gib 29, 29, and is adapted to slide lengthwise upon these latter. To provide for engagement with the detector-pins, the exterior surface 70 of the inner portion of the length of each bar 28 is dropped inward toward the axis of the detector-roll, relative to the corresponding surface of the outer portion of such length, producing a shoulder, 28^a, located 75 at an intermediate point in the said length and facing toward the middle of the machine. This shoulder is adapted to engage, in movement of the bar toward the middle of the machine, with the inner end of the 80 detector-pin which is covered and held radially retracted by the selvage or margin of the web a. See the lower portion of Fig. 3. Each bar 28 carries a roll, 30, which is mounted upon a stud projecting radially inward from the bar, and the cam-sleeve 8 is formed with a peripheral cam-groove at 8^a receiving the rolls of the series of bars 28, 28, etc. The walls of the cam-groove are so shaped as to tend to move each shouldered 85 bar in turn, in each rotation of the detector-roll, first toward the middle of the machine, and then in the reverse direction, namely, toward the end of the detector-roll. The movement toward the middle of the machine is timed to occur after the bar and the series of detector-pins with which it co-acts 90 have arrived at the under side of the detector-roll, so as to afford those pins of the said series which are unconfined by the 100 marginal portion of the web a full opportunity, before such movement takes place, to gravitate into their outermost position, radially, as in the case of the outermost two pins in the lower part of Fig. 3. The movement of the bar 28 toward the middle of the machine, due to the action of the cam-grades of the walls of the cam-groove of the cam-sleeve upon the roll 30, proceeds 105 until the shoulder of the bar encounters a 110 pin in radially retracted position. This encounter arrests such inward movement, and thereupon the said roll, as it is carried around by the detector-roll in the rotation of the latter, acts by its pressure against the said 115 cam-grades to force the cam-sleeve and the leading side of the connected annulus outward away from the middle of the machine to the extent of the remainder of the throw of the cam-grades. The tension of the 120 springs (72, 72, etc., in the prior patent) by which the selvage bars or blocks are drawn toward the middle of the machine, and which is transmitted through the said bars or blocks and the anti-friction rolls 13, 13, 125 etc., carried thereby to the annulus at each side of the machine, acts to oppose this outward movement of the cam-sleeve and annulus, and holds the shoulder of the bar 130 pressed firmly against the pin with which it

is engaged. Such tension acts also, in case the selvage or margin of the web should sway inward so that fewer pins of the succeeding series are covered and held retracted thereby, to swing the annulus toward the middle of the machine and move the cam-sleeve and assemblage of bars in the same direction until the shoulder of the bar coming into action brings up firmly against the inner end of the outermost pin that is held retracted by the web. On the other hand, should the selvage or margin sway outward, the shoulder of the latter bar will engage with a pin of the said succeeding series nearer the outer end of the detector-roll, and by arresting the inward movement of the bar before the cam-grades cease to act will bring about the outward shift of the cam-sleeve and leading side of the annulus which is necessary to place the annulus in proper working position.

To enable the delivery sides of the annuli at the opposite ends or sides of the machine to be set or adjusted nearer together or farther apart according to the width of the web to be operated upon, or otherwise according to the distance between the paths which it is intended the opposite selvages or margins of the web shall follow in passing inward, each pivot-pin 12 is engaged with a block 40, the latter being mounted in manner enabling it to be shifted toward or from the middle of the machine. Each block 40 has an opening made horizontally therethrough, through which the arm 11^c of the corresponding annulus projects. The pivot-pin 12 projects upward from the said arm into a slot 401, Fig. 12, in the cover or top of the said block. This slot permits the pivot to move forward or rearward as the annulus is turned or swung in being adjusted at its respective sides. The two blocks at the opposite sides of the machine are formed with sleeve-portions 41, 41, which fit upon a transversely extending rod or shaft 42 that is supported at its ends by bearings with which the side-frames of the machine are provided. The said rod or shaft is formed with right and left screw-threads near its respective ends, and the sleeves 41, 41, are internally threaded to engage the threads of the rod or shaft. By rotating the rod or shaft, as by means of the handle 43, the blocks and the delivery sides of the annuluses may be shifted nearer to or farther from each other.

Each annulus 11 is formed at its receiving side with a receiving section 11^d which has the acting surface thereof concentric with the pivots which connect the annulus with the corresponding yoke 10. See the dotted lines in Fig. 11. As a consequence of this concentricity, the changes in the inclination of the annulus which occur from time to time in the working of the machine, either as a result of the automatic adjustment of the yoke and

annulus, or as a result of the adjustment by hand of the pivot 12, will have no effect upon the approach of the rolls 13 to the pivotal axis. At the place at which the web passes on to the selvage positioning bars or blocks, the rolls always will approach to within the same distance of the said pivotal axis, unaffected by the variation in inclination. Similarly, at the delivery-side, each annulus is formed with a delivery-section 11^e which has the acting surface thereof concentric with the axis of the pivot 12. As a consequence, the distance horizontally between the rolls when in contact with such section and the line of the said axis will be unaffected by the movements of the annulus as it is swung in and out at the receiving side thereof by the action of the automatic mechanism. The length of the concentric receiving and delivery sections 11^d, 11^e, is sufficient to permit considerable latitude of variation in the height at which the web arrives upon the edge-positioning bars or blocks in passing from the delivery-roll, and also in the height at which the web leaves the said edge-positioning bars.

For the purpose of rotating the detector-roll and the series of positioning bars or blocks, a sprocket-wheel 50 is fixed upon one end of the hollow shaft 9, of the detector-roll, and a sprocket-wheel 51 is fixed upon the shaft 14 of the rotary series of bars or blocks. A band-pulley, 52, is mounted to turn upon a stud, 53, which is applied to one side-frame, 1, of the machine, this band-pulley being provided with a connected sprocket-wheel 54. A sprocket-chain, 55, passes around the sprocket-wheels 50 and 54, and one rim thereof engages with the sprocket-wheel 51. When the said band-pulley 52 and sprocket-wheel 54 are driven by means of a suitable driving-band applied to the former thereof, movement of rotation in the required directions is transmitted by means of the sprocket-chain 55 and sprocket-wheels 50 and 51 to the detector-roll and series of positioning bars or blocks.

It is to be understood that the essential function of the detector-roll, detector-members carried thereby, and automatic adjusting means operating under control of the said detector-members, is to bring about a relative shift between the edge of an advancing web and the devices or part to which the web or the said edge is to be delivered, and that the features of invention in connection therewith, broadly considered, are not necessarily restricted with respect to the particular construction of the parts above specified, or of the machine in which they are employed, or to the precise manner in which the said shift is attained.

What is claimed as the invention is:—

1. The rotating detector-roll having the detector-members operated by gravity, com-

130

- 6 bined with engaging means arranged to engage with web-retracted members at a point in the rotation of the said roll where the members not thus retracted occupy gravity-imparted positions clear of such means.
2. The rotatable detector-roll having the detector-pins which are movable radially by gravity, combined with engaging means arranged to engage with the web-retracted pins at a point where the pins not thus retracted occupy gravity-imparted positions clear of such means.
3. In combination, the rotatable detector-roll having movable detector-members, the cam, edge-positioning devices under the operative control of the said cam, and a movable member interposed between the said detector-members and cam for engagement with the said detector-members, and adapted by reciprocal action to operate the cam for the purpose of varying the action of the edge-positioning devices.
4. In combination, the rotatable detector-roll having movable detector-members, the cam, edge-positioning devices under the operative control of the said cam, and a series of movable members interposed between the said detector-members and cam for engagement with the said detector-members, operated by the said cam and adapted, reciprocally, to operate the cam for the purpose of varying the action of the said edge-positioning devices.
5. In combination, a rotatable detector-roll, detector-members carried thereby and controlled by the marginal portion of an advancing web, a shifter-cam, and a plurality of interposed members operatively engaged with the said cam and moved thereby transversely with relation to the web, each of the said interposed members operating, when arrested in its transverse movement by a detector-member, to shift the cam laterally by contact with the cam-surface thereof.
- 45 6. In combination, detector-members controlled by the marginal portion of an advancing web, a shifter-cam, and a member which is moved by the said cam transversely with relation to the detector-members, and which 50 when arrested in its transverse movement by a detector-member, shifts the cam laterally by pressure thereagainst.
7. In combination, the rotatable detector-roll having detector-members, the yieldingly-actuated laterally movable shifter-cam, and a movable contact-member in engagement with the shifter-cam and which, when also engaged with a detector-member, acts against the shifter-cam to occasion lateral movement of the said cam.
- 55 8. In combination, the rotatable detector-roll having the movable detector-members for engagement with the marginal portion of a web, engaging means coöperating with the said detector-members, edge-positioning devices operatively controlled by the said engaging means, and means to adjust the said detector-members transversely with reference to the web.
9. In combination, the rotatable detector-roll having the movable detector-members for engagement with the marginal portion of a web, engaging means coöperating with the said detector-members, edge-positioning devices operatively controlled by the said engaging means, and the screw-threaded shaft whereby the said detector-members are adjusted transversely, with reference to the web.
10. In an automatic web-guide, in combination, the rotatable detector-roll having movable detector-members, the laterally-movable cam, edge-positioning devices operatively controlled by the said cam, and a movable contact-member in working relation with the cam and adapted for engagement with a web-retracted detector-member.
11. In combination, the rotatable detector-roll and detector-members carried thereby, edge-positioning devices operatively controlled by the said detector-members, and means to adjust the said edge-positioning devices to vary transversely the path of the edge of the web in being delivered by such devices.
12. In combination, the rotatable detector-roll and detector-members carried thereby, edge-positioning devices operatively controlled by the said detector-members, means to adjust the detecting members transversely with reference to the width of the web operated upon, and means to adjust the said edge-positioning devices to vary transversely the path of the edge of the web in being delivered by such devices.
13. In combination, a rotatable detector-roll and edge-detecting devices for an advancing web carried thereby, traveling edge-positioning devices, means in connection with the said edge-detecting devices for automatically adjusting the edge-positioning devices at the receiving side thereof, means for adjusting the edge-detecting devices transversely with relation to the width of the web at will, and means to adjust the edge-positioning devices transversely at the delivery-side thereof to vary the path of the edge of the web as it leaves the devices last named.
14. In an automatic web-guide, in combination, traveling edge-positioning devices, a swinging guide therefor, edge-detecting devices, and automatic adjusting means controlled by the said detecting devices and in pivotal connection with the leading side of the swinging guide, the said guide having a receiving section which is concentric with the pivotal axis of such connection.
15. In an automatic web-guide, in combination, traveling edge-positioning devices,

a swinging guide therefor pivoted at its delivery side, edge-detecting devices, automatic adjusting means controlled by the said detecting devices and in pivotal connection 5 with the leading side of the said swinging guide, and means to adjust the pivot at the delivery side transversely, the said guide having a receiving section which is concentric with the pivotal axis of the said pivotal

connection, and also having a delivery section which is concentric with the adjacent pivot.

In testimony whereof I affix my signature in presence of two witnesses.

WILLARD I. LEWIS.
